United States Patent Office

Des. 201,831
Patented Aug. 3, 1965

201,831

SCAFFOLD FRAME

Arthur C. Borgman, 530 5th Ave., Franklin Square, N.Y.

Filed Apr. 24, 1963, Ser. No. 74,596

Term of patent 14 years

(Cl. D54—1)

FIG. 1

FIG. 2

FIG. 1 is a front elevational view of a scaffold frame member.

FIG. 2 is an elevational perspective view of a scaffold frame.

The dominant features of my design reside in the portions shown in full lines on the drawing.

I claim:

The ornamental design for a scaffold frame, substantially as shown and described.
